(57) CLAIM

The ornamental design for a jar, as shown and described.

DESCRIPTION

FIG. 1 is a top front perspective view of a jar, showing our new design;

FIG. 2 is a bottom rear perspective view thereof;

FIG. 3 is a front elevation view thereof;

FIG. 4 is a rear elevation view thereof;

FIG. 5 is a left elevation view thereof;

FIG. 6 is a right elevation view thereof;

FIG. 7 is a top plan view thereof; and,

FIG. 8 is a bottom plan view thereof.

The broken lines in FIGS. 1-3 and 5-8 are included for purposes of illustrating a lid portion of the jar that form no part of the claimed design.
